UNITED STATES PATENT OFFICE

HENRY J. ERNST, OF NEWPORT, KENTUCKY

DRIER

Application filed October 18, 1927. Serial No. 226,982.

My invention relates to drying apparatus and particularly to a novel type of drying apparatus for blankets and other cloth fabrics in sheets which combines a stretching 5 operation with the drying operation.

It is my object to provide a dry house having controlled air currents, and to have a carriage on which drying and stretching apparatus will be mounted, which can be automatically inserted and withdrawn from the dry house. It is an object to provide 10 drying and stretching apparatus which will convey the sheet of material to be dried into an arch-like formation which will expose it 15 efficiently to the drying air currents.

It is further my object to provide mechanism which will be operable conjointly with the mechanism which conveys the sheet into an arch-like formation, and which will 20 stretch the sheet being dried in the direction both of its length and breadth.

Broadly, it is my object to provide an improved drier for blankets, particularly 25 woolen blankets, which will materially cut down the necessary drying time, and which will also lessen the likelihood of damaging the blankets during the drying and stretching operation. I further have as an object the provision of a feeding device which will 30 feed the blankets onto a carding rope which engages the edges of the blankets, thereby sparing the hands of the feeder operators from being scratched by the card rope.

The above and other objects to which reference will be made during the ensuing disclosure I accomplish by that certain arrangement and combination of parts of which I have shown a preferred embodiment.

In the drawings:-

40 Figure 1 is a front elevation of the interior of the drying mechanism with the obstructing front wall of the dry house not shown.

Figure 2 is an end elevation of the drying mechanism showing the dry house walls in 45 section.

Figure 3 is a sectional view taken along the lines 3-3 in Figure 1.

Figure 4 is a horizontal sectional view of the carding rope taken along the lines 4-4 50 in Figure 3.

Figure 5 is an enlarged sectional view of the bottom part of stretching mechanism shown in Figure 3.

Figure 6 is a sectional view of the base of the stretching mechanism as it would appear from the position indicated by the lines 55 6-6 in Figures 3 and 5.

Figure 7 is an enlarged view of the gear shifting mechanism for inserting and withdrawing the drying mechanism from the dry 60 house.

Figure 8 is a view of the parts shown in Figure 7 as they would appear from the position indicated by the lines 8-8 in Figure 7.

Figure 9 is a perspective view of the telescoping reels over which the sheet of flexible material is drawn by the carding ropes.

Figure 10 is an end elevation of the sheet tensioning mechanism which makes the hand feeding of the sheets onto the drying mechanism unnecessary.

Figure 11 is a side elevation of the tensioning mechanism shown in Figure 10.

Generally indicated at 1 in Figure 1 is the dry house which may be of preferred construction, being usually made of sheet iron. The top portion of the dry house is formed so as to make a slanting air duct 2 through which the exhausted drying air is drawn to a blower 3. The blower is run by a belt 4 from a motor 5 which also drives the intake air blower 6. The intake air blower has an intake pipe 7 from some source of air and a delivery conduit 8 in which I have shown heating coils 9. The conduit 8 has a series 75 of diverting panels 10, 11 and 12, which subdivide the air into three or more distinct channels. Pivoted shutters 10^a, 11^a and 12^a extend into the path of the incoming air. The shutters are held open when the drier is 80 in the house by extensions 10^b, 11^b and 12^b. The extensions are extended from the drying rack and move with it. As soon as the drying rack is moved out of the house the extensions 85 10^b, 11^b and 12^b move out of positions holding the shutters 10^a, 11^a and 12^a open, and the shutters are blown shut. By varying the length of the extensions 10^b, 11^b and 12^b 90 the shutter 10^a may be closed first, 11^a next, and 12^a last, so that when the drying rack 95 100

moves the length of the extensions 10^b, 11^b and 12^b the entire air supply will be shut off. At the top of the dry house I have provided a series of shutter panels 13 which may be 5 opened or closed as desired by a rod 14 and a lever handle 15 located at some convenient position for the operator of the drier to reach. The particular construction of the drying system may be changed in accordance 10 with particular requirements, it being my idea to show only one combination which will be found to operate satisfactorily. The currents of heated air should be forced in at the bottom and pass up through and around 15 the drier and there be exhausted. In some instances it may be preferable not to provide a fresh intake of air for the blower, but to merely circulate the air around in a circuit such as I have diagrammatically described. 20 The drying apparatus is mounted on frame members 16 which have supporting casters 17 at the front and back which ride on rails 18. I have provided a mechanical drive for inserting and withdrawing the drying apparatus 25 from the dry house. A large cog wheel 19 is mounted on a shaft 20 which extends across the frame 21 on which the drying mechanism is mounted. The shaft 20 has a pair of bevel gears 22 slidably mounted thereon with keys. 30 Each bevel gear has a shifting fork 23 which moves the bevel gear into engagement with the bevel pinion 24 carried on the main drive shaft 25 which is driven by a worm gear 26 which engages the pinion 27 on a motor 28 35 mounted at the top of the drying mechanism framework. The shifting forks 23 which are pivoted on shafts 23^a have rollers 29 mounted at their ends which are engaged at the inner and outer limits of movement of the drying 40 mechanism by lugs 30 having slanting engagement surfaces. The object of such an arrangement will be obvious. When the operator pulls, for example, on a shifter handle 31 mounted on a shaft 23^a, the drying apparatus 45 will be moved into or out of the house. It is important that the drying apparatus should be stopped when it is completely in or completely withdrawn from the dry house. The weight of a roller 29 is sufficient to hold in 50 the clutch until such time as the roller is elevated by the inclined lug at the end of the limit of movement of the drying apparatus. With the ordinary rack type drier in which a drying rack is hand pulled and pushed into 55 and out of a dry house, frequent damage to both the rack and dry house is done by a careless operator who slams in the rack without regard to the damage which may be done. By providing a mechanically controlled 60 movement which is automatically shut off at the ends of movement of the drying apparatus all tendency to damage the drying apparatus is avoided. It will be obvious from reference to the drawings, particularly Figure 65 7, that one of the shifting handles 31

will set the mechanism in operation for moving the drying apparatus into the dry house and the other will set the apparatus in operation for withdrawing the drier. The particular shifting devices indicated are merely representations of how the driving mechanism can be controlled. Different arrangements within the knowledge of a skilled mechanic may be used by way of modification. 70

The mechanism for carrying the sheet of material to be dried into an arch-like formation and then stretching it is composed of a pair of telescoping reels, one of which is an upper reel 32 mounted with a key on a shaft 33 extending longitudinally from one end of the mechanism frame to the other, the shaft being journaled as indicated at 34, 35 and having the front end of the shaft 33 carrying a bevel gear 36. The lower reel 37 is mounted on a shaft 38 in vertical alignment with the shaft 33, and the shaft 38 has an end 39 extended at one end on which is mounted a bevel gear 40. The bevel gears 40 and 36 always move in the same direction being driven by the pinions 41, 42, which are mounted on the vertical shaft 43. The shaft 43 is driven in clockwise or counterclockwise direction by means of a pair of bevel gears 44, 45, the bevels of which face one another. The gears 44, 45, are carried on a sleeve 46 mounted on the shaft 25. A shifting rod 47 moves either one or the other of the bevel gears into engagement with a bevel gear 48 which is mounted on a countershaft 49 which drives the shaft 43 by means of the pinion 41. 95

Extending in toothed pulleys 50 in the end hubs forming the reels are the two continuous bands of carding rope 51 which are preferably backed by the flexible band of metal 52. The band of metal and the carding rope may be held together by a series of metal clips such as are indicated at 53. The edges of the metal clips 53 are flanged over as indicated at 54, to reinforce the assembly and the carding rope, backing strip and clips form a continuous loop extending about the pulley portions of the reels, the bodies of the clips being engaged in the notches in the pulleys. A pair of metal plates 55 having portions cut out for the shafts 33 and 38 extend between the shafts. These plates are held together by the brackets 56. Fixed in between the plates are nuts 57, 58 which are moved inwardly or outwardly by the screws, the operation of which will be hereinafter described. The outer edges of the plates have attached thereto the guard plates 59, 60, which keep the carding rope assembly properly aligned. Flanged portions 61, 62, extend about the carding rope assembly to guide it properly. The nuts 57, 58, are engaged by the screw-threaded portions of the shafts 63, 64, which extend through the side of the frame and are provided with thrust bearings as indicated at 65, 66. The outer ends of the shafts 63, 64 130

are provided with bevel gears 67, 68 which are driven by the bevel pinions 69, 70 mounted on the countershaft 71.

The countershaft 71 is driven in a similar manner as the countershaft 43 having a shifting rod 72 which meshes one or the other of two bevel gears 73, 74 arranged in opposed position on the shaft 25, and which drive the gear 75 of the countershaft 76 on which the bevel pinion 70 is mounted.

10 A fixed band of carding rope is arranged as indicated at 77 so that when the blanket has been drawn over the upper reel the end may be fixed and some further stretching of the blanket longitudinally may be obtained by further movement of the shaft 33.

15 For feeding a blanket to the stretching device I have provided the screen 78 which may be pulled out when the drier is withdrawn from the dry house and the moist blanket or sheet disposed on it. Extending across between aligned positions on the continuous bands of carding rope I have shown the starting strip 79 which is of carding rope mounted 20 on a metal bar 80 which is guided in curved guide plates at the front end of the assembly so that should a narrow blanket be dried the strain on the outer end of the bar will not be so great as to cause it to bend out of shape.

25 Supposing that the drier is withdrawn from the dry house and the operators are placing a blanket on the drier, the first operation is to withdraw the screen 78 and fold up the wet blanket or sheet of material on it. The operators first extend their hands 30 through the tensioning device and mount the front edge of the blanket on the starting strip 79. The starting strip 79 is fixed at its inner end and slidably retained in a clip 79 which is attached to the outer one of the carding rope assemblies. The lever 47 is then shifted and the blanket will be fed from the starting position up over the top reel the distance which it will be drawn on the return bend 35 on the other side of the upper reel being dependent on the length of the blanket. When the end of the blanket has been reached the two operators take the end of the blanket and fix it on the fixed band 77. The lever 72 is 40 then shifted and the outer carding rope assembly is pulled away from the inner fixed assembly sufficiently to stretch the blanket tight. While the lateral stretching is being carried on a further slight stretch may be 45 given to the blanket by continuing the feeding movement of the shafts 33, and 38.

50 The tensioning device which I believe to be entirely new is composed of a pair of brackets secured to the frame of the drier which carry the rollers 81 and a pair of friction plates. The sheet is fed between the rollers 81 and the carding rope assembly. The rollers 81 are mounted on curved arms 82 which are connected with friction plates 83. 55 The plates 83 are pivotally mounted as indi-

cated at 84 on the bosses 85 extended from fixed friction plates 86. The ends of the plates 83 have extensions carrying handles 87. Springs 88 mounted on studs 89 extending through the plates 86 tend to keep the extensions of the plates 83 pressed away from the plates 86 so that the friction surfaces of the plates 83 will be pressed against the plates 86. The tensioning devices are arranged at an angle to the carding rope assembly so that when the operator presses down against the handles 87 the rollers 81 are moved away from the carding rope assemblies, and at the same time the friction surfaces of the plates are moved apart so that a blanket may be 60 either inserted or withdrawn without difficulty.

Having thus described my invention, what I claim as new and desire to secure by Letters Patent, is:—

1. A carriage for cooperation with a drier chamber, said carriage having thereon means for mechanically conveying a sheet into an arch-like formation, said carriage also having thereon mechanical means for stretching the sheet laterally operatively connected with said first mentioned mechanical means, and mechanical means for moving said carriage into and from said drier chamber.

2. A carriage for cooperation with a drier chamber, said carriage having thereon means for mechanically conveying a sheet into an arch-like formation, said carriage also having thereon mechanical means for stretching the sheet laterally operatively connected with 95 said first mentioned mechanical means, and mechanical means for moving said carriage into and from said drier chamber, and stops being provided to inhibit the operation of said last named mechanical means at the end 100 of its limits of movement.

3. The combination in a drier for sheet material of the type having a dry house and a drying rack for holding a sheet of fabric in an arch-like formation opening downward 105 so as to expose the inner surface thereof to circulating air currents, of blower mechanism for forcing air into the bottom and out of the top of the house, mechanical means for inserting and withdrawing said rack from said dry house, and means for stopping said mechanical means at predetermined limits of its movement.

4. A drying rack for holding a sheet of fabric in an arch-like formation so as to expose the inner surface thereof to circulating air currents in a dry house, said drying rack provided with means for mechanically conveying a sheet of fabric into an arch-like formation thereon, and a tensioning device for feeding a sheet of fabric onto said rack during the mechanical conveying thereof, said tensioning device comprising a pair of rollers adapted to engage the ends of the sheet 115 120 125 130

and friction plates through which the sheet will be drawn.

5. A drying rack for holding a sheet of fabric in an arch-like formation so as to expose the inner surface thereof to circulating air currents in a dry house, said drying rack provided with means for mechanically conveying a sheet of fabric into an arch-like formation thereon, said conveying means comprising endless belts having carding rope thereon for engaging edges of a sheet to be dried.

6. In combination with a drying chamber, a frame movable into and out of said chamber, supporting and driving means on the frame, a pair of belts on said means provided with projections to which a sheet of material will adhere, one of said belts having its supporting and driving means movable bodily laterally with relation to the other to stretch the article.

7. In combination with a drying chamber, a frame movable into and out of said chamber, supporting and driving means on the frame for a pair of belts provided with projections to which a sheet of material will adhere, a pair of said belts thereon, one of said belts having its supporting and driving means movable bodily laterally with relation to the other to stretch the article, a motor for said frame, and connections therefrom to operate said driving means, and a frame moving mechanism also having connections to the frame to move it into and out of the chamber.

8. In a drying rack, the combination with a frame, of a rotating element having a surface to which a sheet of material will adhere, and means for rotating said element, and devices for placing tension on a sheet of material as it is drawn over said rotating element, a motor for said rack and connections therefrom to operate said driving means, a propelling device for said rack and connections from the motor thereto.

45. In a dry house having a clothes drying rack removable therefrom, a series of drying air directing conduits constructed and arranged to direct air currents through different portions of said rack and having shutters for blocking the passage of drying air therethrough, and said clothes drying rack having means so arranged with relation to said shutters as to open the same with the complete insertion of said rack within said dry house and to close the same with the withdrawal of said rack from said dry house.

10. The combination of a dry house having a clothes drying rack removable therefrom and a series of drying air directing conduits constructed and arranged to direct air currents through different portions of said drying rack and each having a shutter movable into the path of an inwardly directed air current, means connected with said drying rack for holding said shutters open when the rack

is within the dry house so that with the removal of the rack from the dry house said shutters will be blown shut by the air current.

11. The combination of a dry house having a clothes drying rack removable therefrom and a series of drying air directing conduits constructed and arranged to direct air currents through different portions of said drying rack and each having a shutter movable into the path of an inwardly directed air current, means connected with said drying rack for holding said shutters open when the rack is within the dry house so that with the removal of the rack from the dry house said shutters will be blown shut in sequence by the air current.
